UNITED STATES PATENT OFFICE.

MATTHEW A. CLARK, OF BROOKLYN, NEW YORK.

PHONOGRAPHIC APPARATUS.

Application filed August 29, 1921. Serial No. 496,195.

To all whom it may concern:

Be it known that I, MATTHEW A. CLARK, a citizen of the United States, and a resident of the borough of Brooklyn, county of 5 Kings, city and State of New York, have invented certain new and useful Improvements in Phonographic Apparatus, Etc., of which the following is a specification.

My improvements relate to phonographic apparatus and cabinets or containers therefor, and are designed to adapt the same more particularly to household use and requirements, by effecting the delivery of the sound vibrations in such manner as to obviate 10 harshness of tone; by rendering the whole apparatus compact and economical as regards floor space, while adapting it to convenience of manipulation, and the available storage of records, etc.; and also for 15 use for other purposes,—the invention consisting in the specific construction, combination and arrangement of parts and appliances described and claimed,—all as herein-after fully set forth.

25 In the accompanying drawings,

Fig. 1, is a front elevation of my improved phonographic apparatus, closed;

Fig. 2, is a central vertical sectional elevation thereof, opened up;

30 Fig. 3, is a sectional detail, upon a larger scale, of the shutter mechanism;

Fig. 4, is a detail view of the crank lever provided for the actuation and control of said shutter mechanism;

35 Fig. 5, is an elevation of the right hand side of the cap section of the casing;

Fig. 6, is a detail view of the drawer which fits in the cap section of the casing;

Fig. 7, is an elevation of the right hand 40 side of the main or medial section of the casing;

Fig. 8, is a right hand side view of the lower or basic section of the casing;

Fig. 9, is a side elevation of the turn table 45 and motor drawer, closed, but removed from the casing;

Fig. 10, is a side elevation of the turn table and motor drawer, partly extended;

Fig. 10^a, is a transverse section taken upon 50 plane of line 10^a—10^a, Fig. 10;

Fig. 11, is a transverse horizontal section taken upon plane of line 11—11, Fig. 5;

Fig. 12, is a side elevation of the phonograph horn;

55 Fig. 13, is a horizontal section of the record cabinet taken upon plane of line 13—13,

Fig. 14, but showing the doors thereof in open position;

Fig. 14, is a front elevation of the record cabinet, with the doors broken away in part, 60 and the record trays omitted;

Fig. 15, is a side elevation of the motor drawer on a larger scale indicating the position of the motor and the rotatable record table in dotted lines;

65 Fig. 16, is a sectional detail of the motor board or slide bracket apart from the container drawer, and taken upon plane of line 16—16, Fig. 17;

Fig. 17, is a top view of the motor drawer 70 as shown in Fig. 15;

Fig. 18, is a horizontal section taken upon general plane of lines 18—18, Figs. 1, 2 and 5;

Fig. 19, is a sectional detail showing the 75 coupling joint between the basic section and the medial section of the casing.

The casing of my improved phonographic apparatus is made in three sections,—i. e., a basic section B, a medial section M, and a 80 cap section C. The bottom side walls of the medial section M, are formed with flanges m, m, (Figs. 2, 5, 18 and 19) which fit inside the top edges of the basic section B, as indicated particularly in Fig. 19, of the drawings; or, obviously, the reverse or alternative arrangement may be resorted to with like result,—in that the retaining flanges m, may be positioned on the base section B, and fitted in the lower edges of the medial section M,—the object being to detachably 85 couple the latter with the basic section B, for convenience in assembling the parts, etc.

The motor and turn table drawer a, is 90 slidably mounted in the upper part of the basic section B; and beneath said drawer d, is an auxiliary compartment b, which may be utilized for the storage of records, or for analogous purposes, as may be found most expedient,—said auxiliary compartment b, 100 being furnished with front doors b', b', for accessibly closing the said auxiliary compartment b.

The turn-table and motor drawer a, is formed with a removable slide bracket or 105 motor board a', on the under side of which the motor a², is mounted, and on the upper side of which the rotatable record table a³, is positioned, as indicated by dotted lines in Figs. 15 to 18 inclusive, in the drawings. 110 The hand crank a⁴, is positioned upon the upper side of the slide bracket a', and is

connected with the usual wind gearing for the motor a^2 , by means of mitre gears a^5 , as indicated more particularly in Figs. 15 and 16. Its location is such that it is conveniently accessible through an opening m^2 , (see Fig. 18) in the right hand side of the lower portion of the medial section M , of the casing, said opening being closed normally by a door m^3 , shown as open in Fig. 18, and as closed in Fig. 7. This door way m^2 , m^3 , affords convenient access, not only to the actuating mechanism for the re-wind of the motor, and the replacement of records on the turn-table a^3 , but also to the 15 needle and diaphragm or sound box d , mounted in the usual way on the lower extremity of the horn tone arm d' , as indicated in dotted lines in Fig. 2; and likewise to the crank arm k , on the lower end 20 of the rock shaft k' , by means of which the shutters k^2 , k^3 , are operatively controlled, said rock shaft k' , extending through the record cabinet m^4 , and into the manipulatory compartment m^5 , therebelow,—as 25 indicated more particularly in Fig. 2. Thus a person seated or otherwise stationed at the right hand side of my improved apparatus will be in a position to conveniently manipulate and control the operative parts there- 30 of through the medium of the door way m^2 .

The front of the manipulatory compartment m^5 , is closed normally by a horizontally hinged door m^6 , which is also adapted, when open as in Fig. 2, to function as a table 35 or writing desk, it being sustained in horizontal position by two side bracket arms m^7 , pivotally attached to said closure m^6 , and to the inner side walls of the medial section M ,—the inner portions of said bracket arms 40 being longitudinally slotted to allow the brackets to adapt themselves to the opening and closing of said door m^6 , as indicated in dotted lines in Fig. 2.

The lower end of the horn h , is seated in 45 a shelf m^8 , positioned at the back of the manipulatory compartment m^5 , as shown in Fig. 2, said shelf m^8 , being formed with a passage m^{11} , affording communication between the lower extremity of the horn h , and the upper portion of the tone arm h' , which is attached to the under side of said shelf m^8 . The horn h , extends through the top and bottom boards of the record cabinet m^4 , being held in position by cleats m^{41} , m^{41} , as indicated in said Fig. 11. A rear door m^9 , affords access to said screw cleats m^{41} , and to the shelf m^8 ; and as the cap section C , is removable, it will be seen that ample provision is thus made for the installation or removal of the horn etc., for any desired purpose.

A feature of my invention in this connection, is the use of a long high horn extending through and above the record cabinet m^4 , and the positioning of the throat

h' , of the horn above said record cabinet m^4 , as clearly illustrated in Fig. 2, whereby the sound vibrations are emitted at a comparatively high level, overhead, relatively speaking, under ordinary conditions of use, instead as heretofore of approximately directing on or below the level of the ears of the listeners. By this elevation of the discharge throat h' , of the horn above the usual auditory level, I obviate or eliminate the harshness of sound or tone effect incidental to the usual delivery of the sound vibrations at a lower level as is customary in phonograph cabinets heretofore known in the art.

The extension of the horn h , and its throat h' , above the record cabinet m^4 , necessitates the location of the shutters k^2 , above said cabinet. For this reason, I as before stated, extend the manipulatory rock shaft k' , through the said cabinet m^4 , at one side thereof, so that its crank arm k , may be located within the manipulatory compartment m^5 . To the upper end of the rock shaft k' , is rigidly attached a rocker arm k^8 , which is pivotally connected by means of a rod k^4 , with a rock lever k^5 , fulcrumed on a fixed part at k^3 , said rock lever k^5 , being in turn pivotally connected with a shutter bar k^7 , to which the shutters k^2 , are pivotally connected,—said shutters k^2 , being each medially fulcrum-mounted between fixed cross bars m^{10} , m^{10} , on the front of the upper portion of the medial casing M , as shown in Figs. 1 and 2. Thus when the shaft k' , is rocked in the proper direction through the medium of the crank handle k , within the manipulatory compartment m^5 , the shutters k^2 , may be opened or closed more or less, as desired.

The side walls of the record cabinet m^4 , are formed with slide brackets e , e , for the support of the record trays t , t , and the doors n , n , of said cabinet m^4 , are also formed, on their inner sides, with slide brackets e' , e' , coincident in alignment with those (e , e) on the inner side walls of the cabinet m^4 , so that the trays t , t , may be supported in extended position as shown in Fig. 2. In order to insure the parallelism of the doors n , n , and their alignment automatically with the side walls of the cabinet when open, I pivotally connect the lower portions of said doors with rods r , r , which are pivotally connected to each other in turn at 120 their inner ends and to a control rod r' , at r^8 , as shown more particularly in Fig. 13, of the drawings, in which the doors are shown in open or extended position in solid lines, and in closed position in dotted lines, thereby illustrating the function and operation of the control rod r' , and connecting rods r , r , r^2 , being a stop on the floor of the cabinet which limits the outward thrust of said rods r , r , r' . By this means the removal of the 130

record trays bodily from the cabinet is rendered unnecessary, as the doors afford auxiliary or supplementary support therefor when drawn out sufficiently to admit of the removal or insertion of records, as required. This feature not only saves time and labor in the handling and storage of the records, but also obviates danger of misplacement of trays or records, and the inconvenience resultant from the removal of trays from the cabinet and their support temporarily upon extraneous objects.

The cap section C, is provided with a drawer *c*, for use as a container of stationery, record catalogues, etc.—in fact for the convenient storage of any papers or material related to the phonograph, or otherwise, as may be found expedient.

It will be seen that my apparatus is unitary and self-contained in character, provision being made for all the exigencies of use. Furthermore, the operative parts are isolated and protected from extraneous interference or contact, while rendered conveniently accessible for legitimate use. The position of the wind-crank *a*, and the shutter crank *b*, within the manipulatory compartment *m*⁵, and the provision of the side door *m*², enables an operator to sit at the side of the apparatus and control the operation thereof without leaving his seat; while the removable motor drawer *a*, and its detachable motor board *a'*, admit of the convenient and expeditious withdrawal of the motor for purposes of lubrication, etc., thereby obviating the danger of deterioration in this particular, as difficulty of access to the motor has heretofore been a serious obstacle in maintaining the operativeness of apparatus of this character.

The horizontally hinged door *m*⁶, to the manipulative compartment *m*⁵, may be used as a temporary record support, for a writing desk, or analogous purposes; while the auxiliary compartment *b*, may be utilized in various ways, and for various purposes, as may be found most expedient in practice.

In fact the whole apparatus affords a

unique and compact combination and arrangement of co-related parts in a unitary structure, the functions of which all tend to render the phonograph adaptable to harmonious use and service,—the economy of floor space being remarkable in view of the extent of accommodation afforded within the casing, while at the same time the detachable character of the basic, medial and cap sections render the device easily transportable in case of necessity,—a consideration of importance to city dwellers where change of domicile is frequent, and available space limited.

What I claim as my invention and desire to secure by Letters Patent is,

1. In phonographic apparatus of the character designated, a casing comprising a basic section, a medial section, the medial and basic sections having cooperating retaining flanges and a cap section, the basic section adapted to contain a motor and turn-table drawer, and the medial section a manipulatory compartment and a record cabinet, said manipulative compartment being formed with a side door way, and with a frontal closure adapted for use as a foldable desk table, substantially in the manner and for the purpose described.

2. In phonographic apparatus of the character designated, a casing comprising a basic section, a medial section, the medial and basic sections having cooperating retaining flanges and a cap section, the basic section adapted to contain a motor and turn-table drawer, and the medial section a manipulatory compartment and a record cabinet, said manipulative compartment being formed with a frontal closure adapted for use as a desk table and slidale side brackets adapted to support said table in horizontal position, substantially in the manner and for the purpose described.

MATTHEW A. CLARK.
